Inventor,
Joseph B. Kitch
By Vernon E. Hopper, Atty.

Patented May 17, 1927.

UNITED STATES PATENT OFFICE.

JOSEPH B. KITCH, OF ELY, NEVADA.

HEAT RETAINER FOR ENGINES.

Application filed January 9, 1925. Serial No. 1,466.

My invention relates to an improvement in heat retainers for all kinds of gasoline engines, or any internal combustion engine.

The object is to preheat the gasoline and maintain the temperature thereof for the initial supply to the carburetor in cold weather.

The invention really consists of a thermos-bottle adapted to be filled with gasoline from the tank, means for supplying heat to the gasoline on its way thereto, and means for retaining this initial supply of gasoline in the thermos-bottle until it is required for starting the engine.

In the accompanying drawings:

Fig. 1 is a side elevation showing the invention as applied to an engine;

Fig. 2 is an enlarged sectional view through the heat retainer; and

Figs. 3, 4, 5 and 6 are views of the disks forming the control valve.

A, represents a thermos-bottle having the usual vacuum space 1, and a cork 2 for closing the same.

A fuel line pipe 4 leads from the fuel tank through the cork well into the bottle, discharging near the bottom thereof.

Another fuel line pipe 5 extends through the cork to the carburetor. The pipe from the tank is adapted to be coiled around the exhaust pipe of the engine to receive heat therefrom, so as to raise the temperature of the gasoline slightly before entering the thermos-bottle. A valve is formed at the mouth of the bottle just outside the cork. This consists of two stationary disks 6 and 7, to which the adjacent ends of the pipe lines are attached.

A rotary disk 8 is fitted between these two stationary disks 6 and 7. The stud-bolt 9 extends through the center of these disks, and a spring 10 thereon creates the required amount of friction between the disks. The disk 8 has rotary movement limited by the pins 11 extending into the slots 12, and this disk has two ports 13 and 14 in position to register with the adjacent ends of the pipe-lines 4 and 5 when the thermos-bottle is to be filled, or its contents is to be used. This valve is also used for closing these pipes when it is turned to the position shown in Fig. 6.

In operation, cold fuel must be drawn from the carburetor before heated fuel enters same, when the engine is cold and is to be

started. Then the valve from the thermos-bottle is opened, and the preheated fuel therein is sucked through the pipe line 5 into the carburetor, thus causing the engine to start right up freely with fuel that is slightly heated rather than cold fuel.

It is understood, of course, that the valve-disk 8 is closed when the engine is not in use, in order to keep the heated fuel in the thermos-bottle to be used in starting when the engine is cold.

This invention insures proper vaporization of fuel when the engine is in use, and by closing the valve disk 8 to shut the heated fuel in the thermos-bottle, which will be kept warm enough to vaporize properly for a long period of time when the engine is otherwise cold. This idea will apply to all internal combustion engines.

I claim:

1. The combination with an internal combustion engine, and a source of fuel supply communicating therewith, of means for heating the fuel passing to the engine, and heat insulated means for receiving and retaining the heated fuel when the engine has stopped for use in assisting the starting of the engine.

2. The combination with an internal combustion engine, and a source of fuel supply communicating therewith, of means for heating the fuel passing to the engine, and vacuum insulated means for receiving the heated fuel and retaining the same when the engine has stopped for use in starting the engine when the same has cooled.

3. The combination with an internal combustion engine, and a source of fuel supply communicating therewith, of means for heating the fuel passing to the engine, and a vacuum insulated chamber interposed within said communication for receiving the heated fuel and retaining the same in its heated condition after the engine has stopped for use in starting the engine when the same has cooled.

4. The combination with an internal combustion engine, and a source of fuel supply communicating therewith, of means connected with the engine while the same is running for heating the fuel passing thereto, and a vacuum insulated chamber connected with said communication for receiving the heated fuel and retaining the same in its

heated condition after the engine has stopped for use in starting the engine when the same has cooled.

5. The combination with an internal combustion engine, and a main fuel feed line communicating therewith, of means interposed in the main feed line for heating the

fuel passing to the engine, and heat insulated means interposed in the main feed line for receiving and retaining the heated fuel when the engine has stopped for use in assisting the starting of the engine.

In testimony whereof I affix my signature.
JOSEPH B. KITCH.
